UNITED STATES PATENT OFFICE.

EMANUEL W. DUNN, OF OAKLAND, CALIFORNIA.

DESIGN FOR AN ORCHARD-HEATER.

45,592.

Specification for Design.

Patented Apr. 14, 1914.

Application filed December 15, 1913. Serial No. 806,930. Term of patent 14 years.

To all whom it may concern:

Be it known that I, EMANUEL W. DUNN, a citizen of the United States, residing at Oakland, in the county of Alameda and State of California, have invented a new, original, and ornamental Design for an Orchard-Heater, of which the following is a specification, reference being had to the accompanying drawing, forming part thereof.

The figure is a side elevation of the heater.

I claim:

The ornamental design for an orchard heater, as shown.

EMANUEL W. DUNN.

Witnesses:

JOHN H. HERRING,
W. W. HEALEY.
